UNITED STATES PATENT OFFICE.

WILLIAM SISSON GILLESPIE, OF BATH BEACH, NEW YORK.

HINGE.

SPECIFICATION forming part of Letters Patent No. 486,952, dated November 29, 1892.

Application filed March 16, 1892. Serial No. 425,133. (No model.)

To all whom it may concern:

Be it known that I, WILLIAM SISSON GILLESPIE, a citizen of the United States, and a resident of Bath Beach, in the county of Kings and State of New York, have invented certain new and useful Improvements in Hinges, of which the following is a specification, reference being had to the accompanying drawings, in which—

10 Figure 1 is a sectional view of my improved hinge, showing the same closed. Fig. 2 is a sectional view showing hinge open, and Fig. 3 is a plan view showing hinge detached and closed.

15 Like letters of reference indicate like parts in each.

My invention relates to an improvement in a hinge of a kind for which Letters Patent of the United States No. 470,043 were granted 20 to me on the 1st day of March, 1892; and it consists in providing another and more positive means of securing a uniformity of action between the members of one or more hinges on the same door or lid; in providing a means 25 for keeping the crack of a door always closed against observation, no matter what the position of the door, and at the same time making a dust or practically air tight joint when the door is closed, and, further, in providing metallic stops for the different members of a 30 hinge rather than leave this office to be performed by the hinged substance, as shown in my former patent, relation in general being to hinges incased entirely within the door and 35 jamb and invisible when the door is closed. These ends I accomplish in the two former provisions by the employment of two ordinary flat pin-flaps B and C, with an intermediate member connecting them by means of fixed 40 pins, said intermediate member A being formed like a rectangular letter U, with its upper ends terminating in ordinary cylindrical hinge-knuckles and having secured to its bottom part on the inside a piece or strip F 45 of the same rigid material of which the door and jamb are composed and so formed by being hollowed out at the sides as to play or slide on contra-curved surfaces formed on the edges of the door D and jamb E, these curves

being concentric with the pins of said knuckles, 50 thus maintaining a practical contact between the piece F and the edges of door and jamb D and E during the entire convolution of the hinge or parts thereof. A reference to the drawings will show how this piece F, secured 55 to the member A of each hinge and working on the curved edges of the door D and jamb E, will always close the crack, connect the hinges one with another, and thus secure 60 uniformity of operation between their several parts and at the same time form a covered joint when the door or lid is closed, the piece F being so constructed as to never entirely leave the support of nor fail to support 65 the member A or the edges of the door D or jamb E.

In my former patent the thin lips of the door D and jamb E, now shown in connection with the piece F, Figs. 1 and 2, either one striking against the inside of members A, determine 70 the commencement of operation in the opposite knuckle of the hinge, and whereas a frictional resistance greater than the strength of these lips, owing to the weight of a door or other cause, might damage the hinged parts 75 I have provided a stop in the hinge itself, which in the present illustration will only permit a quarter-turn of the flaps B and C on the intermediate member A. This stop I form by making a blank ward with one-quarter removed in the center of each knuckle. The remaining parts of said wards in flaps B and C striking against the remaining part of the wards in member A will form a metallic 80 stop sufficient to avoid any friction in either 85 of the pins or knuckles and prevent any injury to the lips of door D or jamb E. (See knuckles between intermediate member A and B and member A and flap C in Figs. 1, 2, and 3.) Of course it is understood that all of 90 the above may refer to a single hinge as well as to two or more where only one may be used or is necessary.

Having now described the improvement on my hinge, its construction and operation, what 95 I claim as new, and desire to secure by United States Letters Patent, is—

In a concealed hinge, the combination of

two ordinary flat pin-flaps, with a rectangular U-shaped intermediate member connecting said flaps, and a strip secured to the inner side thereof so formed as to maintain contact with the curved surfaces of the edges of the door and jamb during the entire movement of the hinge, substantially as shown and described.

Signed at Brooklyn, in the county of Kings and State of New York, this 10th day of March, 1892.

WILLIAM SISSON GILLESPIE.
